Garfield L. Beckstrom and Richard S. Krause,
Chicago, Ill., assignors to Cory Corporation,
Chicago, Ill., a corporation of Delaware

Application December 4, 1953, Serial No. 27,915

Term of patent 14 years

(Cl. D74—1)

To all whom it may concern:

Be it known that we, Garfield L. Beckstrom and Richard S. Krause, citizens of the United States and residents of Chicago, in the county of Cook and State of Illinois, have invented a new, original, and ornamental Design for a Combined Base and Stand for Pens or the like, of which the following is a specification, reference being had to the accompanying drawing, forming a part hereof.

Fig. 1 is an end elevational view of a combined base and stand for pens or the like embodying our new design;

Fig. 2 is a top plan view of the same;

Fig. 3 is a rear elevational view of the same; and

Fig. 4 is a front elevational view thereof.

The dotted line showing on the drawing is for illustrative purposes only.

We claim:

The ornamental design for a combined base and stand for pens or the like, substantially as shown and described.
